UNITED STATES PATENT OFFICE.

CARL J. JOHNSON AND JOHN E. JOHNSON, OF LOS ANGELES, CALIFORNIA.

SAFETY DEVICE FOR BATHTUBS.

1,405,222.

Specification of Letters Patent. Patented Jan. 31, 1922.

Application filed June 2, 1921. Serial No. 474,483.

To all whom it may concern:

Be it known that we, CARL J. JOHNSON and JOHN E. JOHNSON, citizens of the United States, residing at Los Angeles, in the county 5 of Los Angeles and State of California, have invented new and useful Improvements in Safety Devices for Bathtubs, of which the following is a specification.

This invention is an attachment for bath 10 tubs which provides a convenient device adapted to be grasped by a person in the bath tub in order to prevent slipping or falling.

The attachment affords a handle which may be swung into position to be readily 15 grasped or which when not in use may be readily released and swung to one side where it will automatically yield until subsequently released.

The invention will be readily understood 20 from the following description of the accompanying drawings, in which:

Figure 1 is a plan view of a portion of a bath tub and the water faucet for the same showing one form of the invention adapted 25 to be mounted upon the rim of the bath tub above the water faucet.

Fig. 2 is a side elevation showing this form of the invention.

Fig. 3 is a detail section on the line 3—3 30 of Fig. 1.

Fig. 4 is a detail section on the line 4—4 of Fig. 3.

Fig. 5 is a side elevation showing a modified form of the invention which includes 35 a wall bracket mounted above a built in bath tub.

In the form of the invention illustrated in Figs. 1 and 2, the attachment is mounted upon the rim 1 of a bath tub 2 preferably 40 above water faucet 3 of the bath tub.

The attachment includes a clamp 4 adapted to be received over the rim of the bath tub and held in position by means of a set screw 5.

45 The clamp 4 is vertically extended as a rod 6 having the shell 7 rotatable upon the same, and said shell is provided with a lateral nipple 8 into which is threaded a hollow pipe 9. The pipe 9 is connected at its outer 50 end to a bracket 10 which forms a handle 11 preferably vertically positioned and adapted to be readily grasped by a person in the bath tub in order to assist the person in entering or leaving the bath tub.

55 By rotatably mounting shell 7 upon the rod

6, the handle may be either swung outwardly to the position shown in Fig. 1 and into position to be readily grasped, or may be swung to one side or the other, as shown in dotted lines in Fig. 1, in order to not obstruct the 60 use of the water faucet 3. Means are preferably provided for retaining handle 11 in either operative or inoperative position, and for this purpose a plunger 12 is arranged in pipe 9 and is provided with a coil spring 13 65 for normally projecting a pin 14 at the end of the plunger into engagement with one of a series of circumferentially spaced recesses 15 provided in the rod 6. The plunger may be retracted against its spring 13 so as to disengage the pin 14 and thereby permit swinging 70 of the handle to one of its other positions.

For this purpose a chain 18 preferably extends from the plunger through the bracket 10, and thence through a loop 19 upon the 75 handle 11, so that the end of said chain will be conveniently positioned to the person using the handle. It will be understood that after the handle has been swung from one position to another and the chain 18 released, that the spring 13 will again automatically cause pin 14 to engage in one of the recesses 15 and thereby lock the handle in its new position.

In the form of the invention illustrated in 85 Fig. 5, a device is shown which may be employed in connection with a built in bath tub. In this form of the invention, the rod 6 projects from a wall bracket 4^a which is suitably mounted upon the wall above the 90 bath tub 2^a. The handle attachment in other respects is similar to that previously described.

It will be noted that the device as thus described provides an extremely simple attachment for a bath tub, but affords a very convenient device arranged to be grasped by a person so as to prevent slipping or falling when entering or leaving a bath tub, or standing up, or sitting down therein.

100 It will be readily understood that the foregoing description of the improved device sets forth the essential elements of the same, and that the specific details of construction of the apparatus may vary within wide 105 limits. In practice it will be found desirable to retain sleeve 7 upon rod 6 by means of a cap screw 20 and to so arrange the plunger 21 as to limit the movement of pin 14 into engagement with recesses 12. Thus for ex- 110

ample the rod of the plunger may be provided with a collar 21 adapted to abut against a flange 22 extending inwardly from pipe 9.

Various changes may be made without departing from the spirit of the invention as claimed.

What is claimed is:

1. A bath tub attachment comprising a clamp adapted to engage the bath tub and having a support projecting therefrom, a handle pivotally mounted on said support and adapted to be grasped by a person using the bath tub, means for latching the handle to said support and means on the handle for releasing said latching means.
- 15 2. A bath tub attachment comprising a

clamp adapted to be secured to the edge of a bath tub, a post projecting upwardly from said clamp, there being a series of radially disposed recesses formed in said post, a sleeve 20 arranged for rotation on said post, a handle secured to said sleeve, a spring actuated latch having a portion adapted to enter the recesses in the post to retain the handle in various positions of adjustment on the post 25 and means associated with the handle for releasing the latching means.

In testimony whereof we have signed our names to this specification.

CARL J. JOHNSON.
JOHN E. JOHNSON.
